Primary Examiner — Deanna L Pratt*Assistant Examiner* — Katie Mroczka*(74) Attorney, Agent, or Firm* — NSIP Law(57) **CLAIM**

We claim the ornamental design for a stand for television receiver, as shown and described.

DESCRIPTION

FIG. 1 is a front perspective view of a stand for television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view, in which a television receiver and a symmetric stand for the television receiver are provided in dot-dot-dash broken lines to illustrate an example environment; and,

FIG. 9 is a rear perspective view of FIG. 8.

The broken lines in the figures show portions of the stand for television receiver which form no part of the claimed design. The dot-dot-dash broken lines showing of the television receiver and the symmetric stand for the television receiver in FIGS. 8 and 9 are for the purpose of illustrating environmental structure only and form no part of the claimed design.
